MAGNETO

Jean Bernard, Paris, France

Application March 9, 1937, Serial No. 129,898
In France March 10, 1936

8 Claims. (Cl. 171—209)

The present invention which relates to magnetos more particularly to the magnetos of aero-plane engines, has principally for its object a spatial grouping of the usual members of a magneto and various special arrangements procuring considerable advantages of weight, bulk, accessibility and strength.

The grouping is remarkable in particular by the fact that as the distributing mechanism has its 10 spindle connected to that of the rotary inductor by a pair of bevel pinions, the fixed body of the distributor is placed right against the coil which is itself located as near as possible to the inductor in the angle formed by the two axes where 15 the fixed body of the distributor and the inductor are partially located, the whole arrangement being mounted in a case closed by a cover covering both the coil and the distributing mechanism.

The proximity of the coil to the distributing 20 mechanism enables the secondary current to be brought to the latter directly by a radial conductor connected to a secondary current take off placed on the coil and entirely enclosed in the case of the magneto, an arrangement which 25 forms a detail object of the invention. On the other hand, it suffices to remove the upper cover to directly expose the coil and all the electric connections as well as the distributing mechanism, and to render same accessible for manipulation.

A special arrangement resides in the fact that the laminated magnetic frame which is embedded in the actual material of the inductor case has 30 no rivets joining the metal sheets. The advantage accruing therefrom is that the entire section of the metal sheets is utilized under the best conditions for the passage of the flux owing to the elimination of the disturbances caused by the rivets which short circuit the sheets.

40 Other special arrangements reside particularly in the fact that the pole pieces are of such a shape that their medial plane is offset relatively to the medial plane of their pole shoes, 45 so as to reduce the bulk of the machine, and also in the fact that the axis of the core of the coil is, for the same reason, offset in the same direction relatively to the said medial plane at the point of junction of the pole pieces with the core; 50 in the fact that the large pinion of the distributor is placed on the outside relatively to the small pinion so that it can be dismounted separately; in the arrangement of a grease cup underneath the distributing gear and of a retaining 55 cup above to prevent the lubricant from reaching

the electric members in the event of the magneto being turned upside down; in the particular arrangement of a set screw enabling the magneto to be held stationary in the ignition position.

5 By way of an indicative and in nowise limitative example, an embodiment of a magneto has been illustrated in the accompanying drawings in the particular case of an inductor having a horizontal axis and of a distributing mechanism having a vertical axis. Said embodiment has 10 the aforesaid improvements as well as other peculiarities which form as many detail objects of the invention.

In said drawings:

Fig. 1 is a vertical section of the machine 15 through the plan containing the spindle of the inductor and the spindle of the distributor, and

Fig. 2 is a corresponding plan view, the fixed 20 body of the distributor being removed as well as the rotary body, the cam and the breakers.

Fig. 3 is a similar view to Fig. 1 of a modified construction.

In said embodiment, the magneto has a rotating inductor 1 keyed on a horizontal shaft 2 which projects from it on either side and which 25 is supported at one end by a ball bearing 3 of a case 4 to serve for driving the magneto. On the opposite side, the case 4 is widely open over a diameter at least equal to that of the inductor 1 and closed by a bolted cover 5 provided with a 30 ball bearing 6 which supports the other end of the spindle 2 which projects from said bearing 6 sufficiently to support a bevel pinion 7. A hole 35 8 of a diameter at least equal to that of the pinion 7 is provided in the cover 5 co-axially with the bearing 6.

Above the inductor 1, in an extension of the case 4, is arranged the magnetic frame having two vertical pole pieces 9, carrying at their lower end the pole shoes, and a horizontal core 10 40 which unites these arms and which is surrounded by the coil 11. The core 10 is fixed at the end by the coil 11. The core 10 is fixed at the end of the pole pieces 9 by clamping plates and screws. To decrease the bulk, the vertical pole pieces 9 are 45 not straight but are cambered by a double curvature so that their upper part is offset towards the driving end of the spindle 2 relatively to the medial plane of their pole shoes. Furthermore the common spindle of the core 10 and of the coil 11 is further offset in the same direction relatively to the medial plane of the upper end of the pole pieces 9, the laminated core expanding 50 55 asymmetrically to the right and to the left on the pole pieces 9.

On the other hand, said laminated pole pieces

- 9 are embedded in the actual material of the case 4 and have no rivets connecting the metal sheets to each other. They are placed in position in the casting mould of the case 4 and their correct relative position is ensured by the fact that they are rigidly connected to each other by a transverse element which is removed during the machining operation; the rivets which hold the metal sheets assembled are arranged in said transverse element and in other appendices arranged so that they are also removed in the machining operation. The most convenient method for this purpose is to cut out said pole pieces in one and the same metal sheet.
- 15 On a level with the coil 11 and right up against it is arranged the fixed body 12 of the distributor which has the shape of an inverted circular cup carrying on its side wall the distributing studs having a vertical axis which intersects that of the shaft 2. Said cup 12 rests with its edge on a plane inner flange of a cup 13 of greater diameter formed by an extension of the upper part of the cover 5. In the space between said two cups 12 and 13 are arranged the rotary body 14 of the distributor, the ignition cam 15, the breakers 16, the condenser 17. Said rotary body 14 is made of insulating material in which is embedded the distributor brush 18. Said rotary body 14 is fixed by screws 19 to which access can be had vertically, on the cam 15 which is keyed on a vertical shaft 20 which passes through the end of the cup 13 along its axis and which is held by a ball bearing 22 lodged below said end in a sleeve 23 which surrounds the shaft 20 at a distance 35 and expands at its lower part forming a fresh inverted cup 24, which merges into the cover 5 and has a local bulge 25 surrounding the whole of the upper part of the pinion 7. On the inside of said cup 24 the shaft 20 carries a bevel pinion 26 located below the pinion 7 and meshing with the latter. A cover 27 closes the inverted cup 24 and carries at its centre a thrust bearing 28 guiding the lower end of the shaft 20 and placed right against the pinion 26.
- 40 In this manner, the two bearings 22 and 28 for guiding the shaft 20 are very far apart and the offset portion of the shaft 20 is very reduced; the large pinion 26 can be withdrawn independently, after simply removing the cover 27; similarly, as the sleeve 23 is of greater diameter than the bearing 22, the shaft 20 can be removed with the pinion 26 after removing the rotary body 14 and the cam 15 by the upper part of the machine.
- 45 The cover 27 forms a grease cup for the pinions 7 and 26. Said pinions are thus abundantly lubricated without danger of the lubricant reaching the electric members of the distributor, which are completely separated from said pinions by the actual end of the cup 13. This separation is further increased by a deflector 29 surrounding the shaft 20 and placed right up against the bottom of the bearing 22. The inverted cup 24 has at its end a central annular projection 30 which causes it to form a kind of annular gutter playing the part of retaining the lubricant in the event of the magneto being turned upside down and of preventing it from penetrating into the cup 13.
- 50 The distributing brush 18 is riveted to the centre of the rotary body on an axial socket 31 which is open at the upper end of the body enclosing a carbon contact 32 rubbing against a stud 22 fixed to the centre of the bottom of the fixed body of the distributor 12 and placed in electrical connection with a resilient contact 34, placed on the coil, by a radial conductor 35 embedded in the bottom of the fixed body 12 of the distributor which is made of Bakelite.
- 55 It will be noted that the whole arrangement thus formed is extremely compact and mechanically very rugged owing to the fact that all the projecting or offset parts of the shafts are very short, and that the inductor, which is the main mass in movement, is in very close proximity to the point of drive of its shaft. Furthermore, the arrangement enables the pinions to be readily inspected, adjusted and lubricated.
- 60 A spring pressed pin 37 is mounted on the cover 27 through which it passes so as to enable it to be operated from the outside and to hold the pinion 26 stationary in the ignition position by engaging in a notch of the latter.
- 65 The upper part of the case 4 and of the cups 12 and 13 is located in the same horizontal plane so as to receive a cover 38 which covers both the coil and the distributor. Said cover is held in place by pivoting bolts 39, carried on the outside of the cup 13, so that they can be readily removed. It holds the cup 12 pressed on its seat by pressing on said cup through the instrumentality of a resilient device 40. The hole 41 in the case 13 for the inlet of the cables to the magneto is arranged so that it can be intersected by this horizontal plane of the joint.
- 70 In the event of its being desired to have a shielded magneto, the whole of the case of the magneto and the cover 38 are made of metal; in the contrary case, the cover 38 can be made of insulating material such as Bakelite and can itself carry the distributing studs; it forms in that case the fixed body of the distributor and the cover 12 can be dispensed with.
- 75 For fixing the magneto on the engine, a strap 42 is provided on the case 4.
- 80 In the modified construction of Fig. 3, the lower part of the case has a shape such that the large pinion 26a which meshes with the pinion 1a keyed on the spindle of the inductor can be mounted above or below said pinion, giving the advantage of enabling the rotary arm to be always rotated in the same direction whatever be the direction of rotation of the inductor. For this purpose, a tubular crosspiece 45 is fitted onto the shaft 20a and is interposed either between the lower fixing nut 46 and the pinion 26a pressed against an upper flange 47 of the shaft 20a, or between said flange 47 and the pinion 26a which is in that case below the pinion 1a of the inductor.
- 85 On the other hand, to enable the relative position of the ignition cam and of the inductor to be accurately adjusted, and the errors of machining to be thus compensated for, the pinion 26a is fixed on its shaft 20a by means of the following adjusting device. There is provided a circular row of p holes pierced through the flange 47 and a circular row of n similar holes pierced through the hub of the bevel wheel 26a. Both said rows have the same diameter and the wheel 26a is secured to the spindle 20a by means of a pin 49a removably fitted in two any registering holes forming respectively part of said rows. It is clearly understandable that by suitably choosing the numbers n and p the adjustment of the bevel wheel 26a on its spindle 20a may be made as fine as desired since the possible angular adjustment of the pinion 26a on its spindle will be equal to

$$\frac{360}{n} \frac{360}{p}$$

or to any multiple thereof.

When the bevel wheel 26a is mounted below the driving pinion 7a its hub engages a flange 48 of the cross-piece 45; said flange is provided with a row of p holes like the flange 47 and the angular adjustment is then made between the hub of the wheel 26a and said flange 48 by means of the pin 49a. In this case, the cross-piece 45 is secured to the spindle 20a by a second pin 49 engaged in one of the holes of the flange 47 and in one hole provided therefor in the upper flange 45a of the cross-piece 45. When the wheel 26a is used in the position shown in Fig. 3, said pin 49 remains in said hole in the flange 45a and its projecting part is housed in one of the holes through the hub of the wheel 26a.

The same Figure 3 also shows a particular device for fixing the ignition cables. Each of the various bosses 50 in which are fixed said cables 51 (only one of which is shown) has a vertical bore in which fits a plug 52 made of insulating material fixed on the end of the corresponding cable. Each plug has a flange 53 and all these flanges are clamped between two annular insulating plates 54, 55 connected together by screws 56 and through one of which, 54, said different plugs pass. A spring 57 in the bottom of the bore of each boss ensures the electric contact between the core of each cable and the corresponding stud of the distributor. The assembly of the two plates and of the plugs is supported by a central rod 59 fixed at the centre of a circular cover 60 carrying a short oblique nipple 61 for the outlet of the cables. The cover 60 closes a hole provided in the assembly cover 38a for the passage of the plugs and of the lower plate 54 whereas the other plate 55 bears on the edges of the hole. As the cover 60 can be turned at will, it is thus an easy matter to bring out the bundle of cables in any desired direction.

Of course the invention is not limited to the details of construction described or illustrated which have only been given by way of example.

What I claim is:

1. In an ignition magneto comprising a rotatable shaft, an inductor keyed on said shaft, a distributor including a circular row of fixed contacts and a stationary body carrying said contacts and a rotary arm and a rotatable spindle carrying said arm, an ignition coil, and a casing enclosing the whole and through which projects one end of said shaft, said coil disposed close to the inductor and having its axis perpendicular to said shaft, a bevel toothed pinion keyed on the shaft end within the casing, said spindle having its axis coplanar and transverse to the shaft axis, a bevel toothed wheel keyed on said spindle and in mesh with said pinion, said casing including two parts secured together, one of which partially encloses the inductor and the coil and the other completes the closure of the inductor and is provided with a cup-shaped portion through the bottom of which extends said spindle, said cup-shaped portion containing the rotary arm and a breaking cam secured on said spindle close to said arm and said stationary body which is cup shaped, externally centered in said cup-shaped portion of the casing and in which projects said spindle and rotary arm, a bearing carried by the bottom of said cup-shaped portion for guiding said spindle, a cover closing a hole in the casing coaxially with said spindle and a bearing for said spindle in said cover.
2. In an ignition magneto as in claim 1, said
3. In an ignition magneto as in claim 1, said casing and cover having cooperating cut-out portions in their wall meeting edge to provide an inlet hole for the bundle of the ignition cables.
4. In an ignition magneto as in claim 1, an abutment on said spindle intermediate the axis of the inductor shaft and the rotary arm carried by said spindle, said abutment being so arranged that the wheel applied against it will mesh with said pinion, and means for holding said wheel applied against said abutment, said means including a sleeve fitted on the spindle and having such a length that when inserted between said abutment and the wheel turned upside down, the latter will again mesh with said pinion but on the opposite side thereof.
5. In an ignition magneto comprising a rotatable shaft, an inductor keyed on said shaft, a distributor including a circular row of fixed contacts and a stationary body carrying said contacts and a rotary arm and a rotatable spindle carrying said arm, an ignition coil, and a casing enclosing the whole and through which projects one end of said shaft, said coil disposed close to the inductor and having its axis perpendicular to said shaft, a bevel toothed pinion keyed on the shaft end within the casing, said spindle having its axis coplanar and transverse to the shaft axis, a bevel toothed wheel keyed on said spindle and in mesh with said pinion, said casing including two parts secured together, one of which partially encloses the inductor and the coil and the other completes the closure of the inductor and is provided with a cup-shaped portion through the bottom of which extends said spindle, said cup-shaped portion containing the rotary arm and a breaking cam secured on said spindle close to said arm and said stationary body which is cup shaped, externally centered in said cup-shaped portion of the casing and in which projects said spindle and rotary arm, a bearing carried by the bottom of said cup-shaped portion for guiding said spindle, a cover closing a hole in the casing coaxially with said spindle and a bearing for said spindle in said cover.
6. In an ignition magneto as in claim 5, a set screw provided on said cover to lock the bevel wheel in the ignition position.
7. In an ignition magneto as in claim 5, said hole coaxial with spindle having a diameter greater than that of the bevel wheel, whereby allowing to easily take off said bevel wheel.
8. In an ignition magneto comprising a rotatable shaft, an inductor keyed on said shaft, a distributor including a circular row of fixed contacts and a stationary body carrying said contacts and a rotary arm and a rotatable spindle carrying said arm, an ignition coil, and a casing enclosing the whole and through which projects one end of said shaft, said coil disposed close to the inductor and having its axis perpendicular to said shaft, a bevel toothed pinion keyed on the shaft end within the casing, said spindle having its axis coplanar and transverse to the shaft axis, a bevel toothed wheel keyed on said spindle and in mesh with said pinion, said casing including two parts secured together, one of which partially encloses the inductor and the coil and the other completes the closure of the inductor and

is provided with a cup-shaped portion through the bottom of which extends said spindle, said cup-shaped portion containing the rotary arm and a breaking cam secured on said spindle close to said arm and said stationary body which is cup-shaped, externally centered in said cup-shaped portion of the casing and in which projects said

spindle and rotary arm, and flange means carried by said first named casing portion perpendicularly to the axis of the inductor shaft for securing the whole magneto upon a support in overhanging position.

JEAN BERNARD.
